(**) Term: **15 Years**

(57) **CLAIM**

We claim the ornament design of a pressure detector, as shown in the attached drawings and described.

(21) Appl. No.: **29/542,032**

DESCRIPTION

(22) Filed: **Oct. 9, 2015**

(30) **Foreign Application Priority Data**

Apr. 9, 2015 (JP) 2015-008028
FIG. 1 is a front view;
(51) LOC (10) Cl. ..... 10-04 FIG. 2 is a right-side view;
FIG. 3 is a plane view;
(52) U.S. Cl. ..... USPC ..... D10/85 FIG. 4 is a bottom view; and,
FIG. 5 is a perspective view when viewed front and right-side top.
This article is a pressure detector which is used on a refrigerator and an air-conditioning machine.
